UNITED STATES PATENT OFFICE.

FRANK E. WAKEFIELD, OF ELGIN, ILLINOIS, ASSIGNOR TO ILLINOIS WATCH CASE COMPANY, OF ELGIN, ILLINOIS, A CORPORATION OF ILLINOIS.

CIGARETTE CASE.

Application filed March 7, 1927. Serial No. 173,256.

This invention relates to a case suitable for containing small articles such as cigarettes and the like, and is concerned with a special cover construction, together with a 5 release means therefor.

It is an object of my invention to provide a small case, suitable for carrying in the pocket or elsewhere, which will have one open side normally closed by a pair of 10 hinged covers in one of which is a container for articles which, when the covers are opened, are presented in a position convenient for withdrawal. In connection with such a case I have aimed to provide spring 15 release means by which both covers may be opened simultaneously in response to pressure manually exerted. The case of this invention is, furthermore, designed with a view to compactness, to be produced and assembled with a minimum of effort and expense, and to withstand ordinary usage over 20 a long period of time.

A suggestive embodiment of my invention is set forth in the accompanying drawing in 25 the manner following:

Figure 1 is a perspective view of the case with the covers in closed position;

Fig. 2 is a similar view with the covers open;

Fig. 3 is a sectional detail view taken on line 3—3 of Fig. 1;

Fig. 4 is a similar view taken on line 4—4 of Fig. 1; and

Fig. 5 is a fragmentary view in plan showing one corner of the case, the covers being partly broken away to expose the release means interiorly thereof.

The case, in the form shown, comprises a generally rectangular body A having a bottom 6 surrounded by marginal walls 7 with an inturned bezel 8. At its two ends the walls may be extended slightly beyond the bezel so as to lie to the outside of proximate marginal walls 9 which depend from three 45 sides of two complementary covers B and C which together form a closure for the case. These covers are connected to opposite side walls of the case as by means of spring hinges 10 each of which tends normally to move its associated cover to an 50 open position, as shown in Fig. 2. In closed position the cover walls may rest upon the bezel which constitutes a stop therefor.

It is preferred that the two case covers 55 should extend from their hinged edges for

unequal distances. The cover designated as B is the larger and extends across the major portion of the open face of the case. The remaining portion of this opening is closed by the cover C so that when both covers are 60 shut, a complete closure is provided, as indicated in Fig. 1. The larger of these two covers may be provided with a pair of supports 11 arranged adjacent the end walls 9 and providing means to which may be connected the opposite ends of a strap or band 12, preferably of elastic material. Between this band and the body of the cover is a space for the reception of such articles as cigarettes D of which four are shown in 70 Fig. 2. The opening movement of the two covers is preferably limited to a position which is substantially perpendicular relative to the case body so that when the latter is rested upon a horizontal surface, the covers will be disposed vertically, when opened up. Accordingly, whatever contents are carried by the cover B are brought to a vertical 75 position with their ends projected upwardly beyond the cover so as to be convenient for removal from the case.

Both covers, when in closed position, are releasably held. This is accomplished by latch devices one at each end of the case, and each, by preference, a duplicate of the 85 other. These devices may include, in each instance, a spring arm 15 having one end 16 secured fast to the case wall 7 between its bezel 8 and the case bottom 6. If desired, a strap 17 connected with the bezel 90 and the case bottom may overlie the spring arm, as shown, at approximately the point where it is required to bend when moved to release position. At its free end the spring arm is connected with a button in the form 95 of a plate 18 which extends through a slot 19 in the end wall 7. Interiorly of the case this button carries a pair of upstanding lugs 20 each having a beveled head 21 providing, in effect, a catch which is adapted to engage 100 with a shoulder 22 formed on the inner face of one cover wall 9 preferably by providing a recess therein. The two catches 21 are so positioned relative to the covers B and C that one will engage each cover. 105 Since a duplicate latch mechanism is provided for each end of the case, it follows that each of the two covers is held at its opposite ends when moved to closed position, as shown in Fig. 1.

2 To open the case, pressure is applied simultaneously to the two buttons 18. Thereupon the catches are released from engagement with the covers so that the latter are 5 free to open in response to the pressure of the springs associated with their respective hinges. The cigarettes or other articles which normally occupy the entire space between the opposite side walls of the case are 10 raised with the cover B. By providing two such covers adapted for simultaneous operation, cigarettes longer than the width of one cover can be carried thereby and brought to an elevated position for removal from 15 the case. This is a feature which conduces to convenience.

A case of the kind described may be made very compact in size. Its contents, such as cigarettes, are secured in place by some such 20 simple means as an elastic strap, so that the withdrawal thereof requires only an end- wise movement, the ends of the cigarettes being otherwise unconfined when the covers are brought to elevated position.

25 I claim:

1. A case having marginal walls, a pair of covers hinged to opposite walls of the case and having spring means for normally swinging to open position, one of the covers 30 providing a closure for the major portion

of the case, means for removably supporting in such cover a plurality of articles having their ends projected beyond the swinging edge of the cover, and a common latch means carried by the case for releasably holding either or both of the two covers in closed position upon the case, substantially as described. 35

2. A case having marginal walls, a pair of covers hinged to opposite walls of the case and adapted conjointly to provide a closure therefor, means for removably supporting in one cover articles which are swung out of the case when both covers are opened, and latch means carried by the case 40 for releasably holding either or both of the two covers in closed position upon the case, substantially as described. 45

3. A case having marginal walls, a pair of covers hinged to opposite walls of the case 50 and providing conjointly a closure therefor, a bezel extending inwardly from the case walls providing a stop for the covers when brought to closed position, and latch means carried by the case providing a releasable 55 catch by which the two covers are normally held independently of each other in closed position, substantially as described.

FRANK E. WAKEFIELD.
